US0D1035382S

(12) **United States Design Patent** (10) **Patent No.:** **US D1,035,382 S**
(45) **Date of Patent:** **** Jul. 16, 2024**

(54) **PUSHER HEAD**

(71) Applicant: **Marmon Foodservice Technologies, Inc.**, Osseo, MN (US)

(72) Inventors: **Mark Fastabend**, Chicago, IL (US); **Aleksandr Yavvin**, Glenview, IL (US); **Scott R. Hammac**, Joliet, IL (US)

(73) Assignee: **Marmon Foodservice Technologies, Inc.**, Osseo, MN (US)

(**) Term: **15 Years**

(21) Appl. No.: **29/740,797**

(22) Filed: **Jul. 7, 2020**

Related U.S. Application Data

(60) Continuation of application No. 29/711,918, filed on Nov. 4, 2019, now Pat. No. Des. 892,551, which is a division of application No. 29/638,669, filed on Feb. 28, 2018, now Pat. No. Des. 869,904.

(57) **CLAIM**

The ornamental design for a pusher head, as shown and described.

DESCRIPTION

FIG. 1 is a perspective view a pusher head;

FIG. 2 is a top view thereof;

FIG. 3 is a bottom view thereof;

FIG. 4 is a left side view thereof;

FIG. 5 is a front view thereof; and,

FIG. 6 is a back view thereof.

The broken lines immediately adjacent the shaded areas represent the bounds of the claimed design while all other broken lines are directed to environment and are for illustrative purposes only; there broken lines form no part of the claimed design.

1 Claim, 5 Drawing Sheets
